UNITED STATES PATENT OFFICE.

FAYETTE A. SPINNEY, OF LA JUNTA, COLORADO.

SPIGOT.

1,011,260.

Specification of Letters Patent. Patented Dec. 12, 1911.

Application filed October 28, 1910. Serial No. 589,634.

To all whom it may concern:

Be it known that I, FAYETTE A. SPINNEY, a citizen of the United States, residing at La Junta, in the county of Otero and State 5 of Colorado, have invented certain new and useful Improvements in Spigots; and I do hereby declare the following to be a full, clear, and exact description of the invention, such as will enable others skilled in the art 10 to which it appertains to make and use the same.

This invention relates to new and useful improvements in spigots for liquid containing receptacles, and more particularly to 15 that class in which the operating valve is to be normally locked in a closed position, so as to prevent any undesired access to the contents of the said receptacle.

An object of this invention is the provision of a device of this character having a 20 valve normally spring pressed in a direction so as to prevent the passage of the liquid from the receptacle to which the spigot is applied, and which is adapted to be automatically forced in a closed position by the 25 tension of the said spring.

Another object of this invention is to improve and simplify devices of this character, rendering them comparatively simple and cheap to manufacture and readily operated.

With the above and other objects in view this invention resides in the novel features of construction, combinations, formations 35 and arrangements of parts to be hereinafter more fully described, claimed and illustrated in the accompanying drawing, in which—

Figure 1 is a fragmentary side elevation 40 of my improved spigot; Fig. 2 is a horizontal view taken through the front portion thereof; Fig. 3 is a front elevation of my improved spigot, and Fig. 4 is a transverse sectional view taken through the closing cap.

Referring to the drawing by characters 45 of reference, the numeral 1 designates a portion of a liquid containing receptacle, to which my improved spigot 2 is applied. This spigot 2 comprises a main tube or hollow body 3, provided at its medial point with a depending discharge spout 4. The body 3 is provided with a longitudinal passage 5, while its outer end is threaded for the reception of a closing cap 6, centrally 50 apertured, as at 7, to permit the outward movement of a longitudinally slidable stem

or pitman 8, carrying keyed to its inner end a piston valve 9 adapted to cover one end of the discharge spout 4 and close the spigot. A peripheral groove 10 is formed in the 60 outer end of the pitman 8 for the engagement of locking disks 11, mounted upon the inner end of rotatable stems 12, carrying upon the opposite side of the cap 6 turn buttons 13, each provided with an indicating finger 14, adapted to point to one of a series of marks or fingers 15 stamped upon the outer face of the said cap. The disks 11, normally engaging the peripheral groove 10 of the stem or pitman 8, are provided with 70 segmental cut away portions which permit the said pitman to pass between the said disks when the indicating fingers 14 are turned to point to a certain predetermined series of characters 15, marked upon the face 75 of the closure or cap 6, as clearly illustrated in Fig. 4 of the drawing.

A substantially L-shaped arm 16 is rigidly secured to the top of the spigot 2, extending slightly in advance of the cap, and 80 carries fulcrumed upon its outer terminal a lever 17, which lever is connected to the outer extremity of the valve stem 8 in such a manner as to operate the piston valve 9 longitudinally of the passage 5 upon any 85 swinging movement thereof. The piston 9 is normally pressed in a direction to cover the discharge spout 4 through the medium of a tension spring 19, engaging the inner faces of the disks 11 and the adjacent end 90 of the piston valve. The inner movement of the said piston valve 9 is limited by means of stops 20, located within the faucet. In order to prevent the valve stem from turning, the inner surface of the longitudinal passage 5 of the valve body is channeled, as indicated by the numeral 21, for the reception of a longitudinal rib 22 formed upon the piston valve 9. 95

From the foregoing disclosure it will be 100 obvious that when the buttons 13 are turned so that the cams 11 will permit the free movement of the stem or pitman 8 through the apertures 7, the lever 17 may be operated so as to move the piston valve 9 away from the discharge spout 4, allowing the free passage of the liquid through the said spigot and discharge spout from the receptacle 1. This piston 9 will be automatically reseated 105 again over the discharge nozzle by merely releasing the lever 14, and manifestly upon the turning of each or any of the buttons 13 110

the spigot will be again locked in its closed position.

From the foregoing it will be readily seen that a spigot is provided for which will answer all the necessary requirements of such a device.

Having thus fully described this invention, what I claim as new and desire to secure by Letters Patent is:

- 10 1. In a spigot provided with a piston valve, a cap upon the said spigot, disks adapted to engage the stem of the valve to lock the valve in closed position, a lever for unseating the valve when the stem is disengaged from the disks, and a spring for automatically reseating the valve upon the release of the said lever.
- 15

2. In a spigot such as described the combination of a valve provided with a peripherally grooved valve stem, cam disks 20 adapted to engage the groove to lock the valve in its closed position, a lever coöperating with the said valve for the purpose of unseating the same when said groove is disengaged from said disks; and a spring engaging the valve stem for the purpose of automatically closing the valve upon the release of the operating lever.

In testimony whereof I affix my signature in presence of two witnesses.

FAYETTE A. SPINNEY.
